UNITED STATES PATENT OFFICE.

AMOS E. WHIPPLE, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

SPINDLE-DRIVING MECHANISM.

1,258,841.

Specification of Letters Patent. Patented Mar. 12, 1918.

Application filed June 1, 1916. Serial No. 101,196.

To all whom it may concern:

Be it known that I, AMOS E. WHIPPLE, a resident of Whitinsville, in the county of Worcester and Commonwealth of Massachusetts, have invented a certain new and useful Improvement in Spindle-Driving Mechanisms, of which the following is a full, clear, and exact description, reference being had to the accompanying drawings, forming 10 a part of this specification.

This invention relates to an improvement in spindle-driving mechanisms in which the spindles are driven from a rotating cylinder by means of endless bands or tapes having 15 frictional contact with the peripheral surfaces of the cylinder and spindle whrils, a group of two or four spindles usually being driven by each tape.

The object of my invention is to provide 20 an improved construction of the tension pulley hanger whereby chafing of the driving tapes against the hanger is avoided and also the hanger is so designed that it may be removed without cutting the tape.

Another and important object is to provide 25 simple means for preventing damage to a tape due to its slipping from its pulley and becoming entangled with adjacent tapes, or winding about the cylinder.

The novel features of my invention will 30 be hereinafter described, and particularly pointed out in the following claim.

Referring to the drawings:

Figure 1 is a transverse sectional elevation 35 of such parts of a spinning or twisting frame as are necessary to show the application of my invention.

Fig. 2 is a plan view of the same showing 40 a group of spindles, their driving tape and its slack take-up.

Fig. 3 is a front elevation of binder pulley hanger showing a preferred form of the tape retainer.

Fig. 4 is a side view of same.

In the accompanying drawings, the spindle rails 1, the spindles 2, their whrils 3, the driving tape 4, the tension pulley 5, and the tape driving cylinder 6 are all of the usual type in common use in spinning and twisting frames. In the usual type of frame the binder or tension pulley 5 is journaled in

bearings fitted in the arms of an inverted U shaped hanger. With this construction the tape is subjected to excessive wear due to chafing against the arms of the hanger. 55 Another objectionable feature is the necessity of cutting the tape whenever it is desired to remove the hanger. By the use of my improved hanger these objectionable features are eliminated. 60

In my improved construction the binder pulley 5 is journaled in bearings 7 fitted in the hook-shaped hanger 8 which is removably connected to the weight arm 9 swinging on rod 10 so that the leverage exerted by 65 the weighted arm takes up the slack in the tape thus maintaining an even tension at all times in the tape. To facilitate the removal of a hanger without cutting the tape the hanger is so designed that the binder pulley 70 is held in two bearings, one in the main leg of the hanger, and the other in an arm of a hook-shaped extension 11 of the main leg in angular relation thereto. The angularity of the extension is so designed that the bottom 75 of the hook is located between the receiving and delivery paths of the tape as it passes about the binder pulley and the hanger is easily removed.

In case a tape should accidentally run off 80 its pulley a guard 16, Figs. 3 and 4, prevents it from becoming entangled with adjacent tapes and the resulting damage thereof. This guard consists of an upwardly extending finger located on the hooked extension 85 of the hanger and so situated that the tape on slipping from its pulley is caught in a pocket formed by the side of the pulley, top of the pulley bearing and the guard.

I claim:

In a spindle driving mechanism, the combination of a driving cylinder, a plurality of spindles, a tape for transmitting motion from cylinder to spindles, a tape binder pulley, a hooked-shaped hanger for the same, 95 and a tape guard consisting of an upwardly extending finger located on the hooked extension of the hanger and substantially parallel with the main leg of hanger.

In testimony whereof, I have signed this 100 specification.

AMOS E. WHIPPLE.
